MAX QUAAS, OF PHILADELPHIA, PENNSYLVANIA, ASSIGNOR TO SANITARY PAPER BOTTLE COMPANY, OF WILMINGTON, DELAWARE, A CORPORATION OF DELAWARE.

TUBE-MAKING MECHANISM.

1,116,735.

Specification of Letters Patent.

Patented Nov. 10, 1914.

Application filed July 3, 1913. Serial No. 777,297.

To all whom it may concern:

Be it known that I, MAX QUAAS, a citizen of the United States, residing in the city of Philadelphia, county of Philadelphia, and State of Pennsylvania, have invented certain Improvements in Tube-Making Mechanism, of which the following is a specification.

This invention relates to machines for making tubes suitable for the bodies of paper containers by winding and applying an adhesive to blanks and setting the adhesive and the laminations of the tubes. It comprises automatic means whereby blanks are rendered adhesive, wound on a longitudinally movable and revoluble mandrel in successive traveling holders, and the tubes delivered from the holders to successive setting devices traveling in proximity to drying mechanism.

The primary object is to provide an improved automatic machine which will perform efficiently and rapidly in synchronous relation the several operations required for winding and setting tubes.

The characteristic features of the improvements are fully disclosed in the following description and the accompanying drawings in illustration thereof.

In the drawings, Figure 1 is a top plan view of the body of a machine embodying the invention, parts being broken away; Fig. 2 is a broken side elevation of the same; Fig. 3 is a broken side elevation opposite that shown in Fig. 2; Fig. 4 is a broken front elevation; Fig. 5 is a broken sectional view taken longitudinally through the mandrel and its operating connections; Fig. 6 is a sectional view taken on the line 6—6 of Fig. 4; Fig. 7 is a broken sectional view taken on the line 7—7 of Figs. 1 and 2; Fig. 8 is a broken sectional view on the line 8—8 of Fig. 4; Fig. 9 is a part sectional plan view of the mandrel and its connections; Fig. 10 is a broken elevation of the paste reservoir and means for operating the pressure roller; Fig. 11 is a sectional view on the line 11—11 of Fig. 1; Fig. 12 is a broken rear elevation of the setting mechanism; and Fig. 13 is a longitudinal sectional view taken through one of the setting devices.

The machine, as illustrated in the drawings, comprises a frame 1 in which is journaled a shaft 2 having thereon the loose driven pulley 3 adapted to be fixed thereto by

the clutch 4, operated by means of the parts 4', 4" and 4'', the shaft having the pinion 5 fixed thereon. A shaft 6, journaled in the frame, has fixed thereon a spur wheel 7, which is engaged by the pinion 5, a drum 8 containing the cam groove 9, and the wheel 10 provided with a segmental cylindrical flange 11 and a lug 12 having a pin 13 thereon disposed equidistant from the ends of the flange. The wheel 10 engages and operates 65 a star wheel 14, revoluble on the shaft 2 and having the concave segments 15 within which the flange 11 revolves sequentially as the wheel 14 is given a step by step movement through the engagement of the pin 13 70 in its radial slots 16. A spur wheel 17, fixed to and revolved intermittently by the wheel 14, engages the spur wheel 18 which is fixed to the spur wheel 19, the latter wheels being loosely journaled on the shaft 6. A shaft 75 20, revoluble and longitudinally movable in the frame, has splined thereon a pinion 21 engaged by the spur wheel 19 and fixed to a pinion 22. An idler pinion 23, journaled by means of the shaft 24, is engaged by the 80 pinion 22 and has fixed thereto a pinion 25. A shaft 26, journaled in the frame, has a spur wheel 27 fixed thereon which is engaged by the spur wheel 25. The pulley 3 acts, through the described intermediate 85 parts, to revolve the drum 8 constantly and the shafts 20 and 26 intermittently.

The drum 8 engages, through its cam groove 9, a roller 28 on a slide 29 in which revolves the shaft 20 provided with the collar 30 engaged by the slide, the latter being movable in the stationary way 29'. A coiled spring 31 is disposed on the shaft 20 between the slide 29 and the end of a sleeve 32 through which the shaft passes and which is revoluble and longitudinally movable in the bushing 33 fixed to the bearing 34', the sleeve having the flange 35 for limiting its forward movement by engaging the bushing. A pin 34 is set in the shaft 20 and projects into the slots 36 in the sleeve 32 so that the shaft and sleeve are permitted a relative longitudinal movement against the action of the spring 31. A spur 37 is telescoped in the sleeve 32 and is projected 105 thereto in movable relation to the sleeve 32 by the studs 38 embedding into the sleeve 32 and sleeve 33 to permit a relative longitudinal movement relatively. A coil spring 39 is disposed on the shaft 20 between the

sleeves to thrust the latter in opposite directions. A short shaft 40 is set in a socket 20' in the forward end of the shaft 20, the shaft 40 having a pin 41 therein which engages a slot 42 in the shaft 20 whereby relative longitudinal movement is prevented and a limited relative rotary movement is permitted. A pin 43 extends through the hub 44 of the shaft 40, passes freely through square holes 45 in the sleeve 36 and projects into diagonal cam slots 46 in the sleeve 32: the cam slots, holes and pin permitting the shaft 40 to turn relatively to the sleeves 32 and 36 and providing for the longitudinal movement of the sleeve 32 relatively to the sleeve 36. A conical mandrel body 47 is fixed to the shaft 40 by its sleeve 48 on the shaft and a pin 49 passing therethrough into the circular slots 50 in the sleeve 36. A conical mandrel sleeve 51 is fixed to the sleeve 36 and turns on the body 47, the latter having a longitudinal flange or lip 52 which is adapted to rock in the longitudinal slot 53 of the mandrel sleeve to engage and disengage the edges 54 of blanks 54 to be wound on the mandrel.

As the drum 8 revolves, the cam groove 9, through its engagement with the roller 28 on the slide 29, causes the latter, through its engagement with the collar 30 and spring 31, to reciprocate the shaft 20 and the sleeve 32 with its connections, the form of the cam groove 9 being of such character as to hold the shaft against longitudinal movement in its forward position, with the mandrel hub 51' in the bearing 51'', for a desired period. When, in the forward movement of the shaft 20, the flange 32' on the sleeve 32 engages the bushing 33, the sleeve is held against further longitudinal movement, and the further longitudinal movement of the shaft 20 causes the short shaft 40 and the mandrel body 47, with the sleeve 48 thereon, to turn in the respective sleeves 36, 32 and 51 through the engagement of the pin 43 with the cam slots 46, the flange 52 being thereby rocked in the slot 53 to engage the edge of a blank 54. When the revolving drum 8 retracts the shaft 20, through the intermediate mechanism, the pin 43 and cam slots 46 cause the shaft 40 and mandrel body 47 to turn in the opposite direction, thus retracting the flange 52 and releasing the tube wound on the mandrel. It will be understood that the relative longitudinal movement of the sleeves 32 and 36, permitted by the apertures 38 and 45, subject to the action of the spring 39, provides for a desired flexibility of action.

60 The winding of the blanks upon the mandrel is effected in the forward position of the latter within the conical holders 55 carried by a wheel 56 which is revoluble on the shaft 6. The holders contain the respective longitudinal slots 55' which are

successively positioned adjacent to the inner edge and approximately in the plane of the table 57 from which the blanks are fed to the mandrel disposed in a positioned holder. When a blank is engaged by the 70 mandrel and is being wound thereon, a segmental conical roller 58, whose periphery revolves in the aperture 57' of the table, engages the inner surface of the section of the blank which forms the lamination or 75 laminations succeeding the first lamination of the tube 54' and applies an adhesive thereto, a roller 58' pressing the blank against the segment in the aperture 57'. The segment 58 is revolved by the shaft 80 26 which acts through the shafts 59 and 60 connected by gimbal joints 61 and 62, as the segment's shaft 60 is journaled in the paste reservoir 63 at an angle to the shaft 26. The adhesive is applied to the 85 segment by the roller 64 fixed on the shaft 65 which is journaled in the paste reservoir; a doctor roller 66, on the shaft 67 journaled in the reservoir, and a scraper 68', acting in contact with the segmental roller to 90 regulate the amount of paste thereon. The several paste rollers are revolved together through the action of the spur wheel 68 on the shaft 60, which engages the pinions 69 and 70 on the respective shafts 65 and 67. 95

The mandrel is inserted in a holder with the slot 53 in registration with the slot 55', the blank 54 is inserted through the slot 55' into the slot 53, the lip 52 is turned to engage the blank, the mandrel is revolved, 100 the gumming segment 58 is turned into contact with the blank, and the roller 58' (lifted by a yoke 60'' movable in guides 58^a by a cam 60' on the shaft 60) descends to press the blank in contact with the segment. As the blank leaves the segment, the roller 58' is elevated by the cam 60' to permit the passage of a second blank, and a cam 58^b on the segment engages a roller 58'' on a lever 58^c having a fulcrum 58''' 110 and elevates a bridge 58^d which supports the blank. When no blanks are being fed to the machine, the roller 58' may be manually elevated and held out of contact with the gumming segment by means of a lever 115 60^a fulcrumed on a bearing 60^c and connected by a link 60^b with the cam 60^d loosely journaled on the shaft 60 and engaging the yoke 60''. When the operation of winding a blank upon the mandrel within a holder 120 has been completed and the mandrel withdrawn from the holder, the holder wheel 56 is revolved by the shaft 6 through the wheel 71 (having the segmental flange 72 and the lug 73 with the pin 74 thereon) 125 which co-operate with the star wheel 75 (having the concave segments 76 in which the flange is adapted to revolve sequentially and the radial slots 77 in which the pin 74 acts); the shaft 78 (journaled in 130

the frame) on which the wheel 75 is fixed and having the pinion 79 fixed thereon; and an internally toothed ring 80 fixed to the wheel 56 and engaged by the pinion 79.

5 The intermittently moving wheel 56 carries the holders 55, with the conical tubes 54' therein, to a position opposite a knocker or plunger 81 which strikes the tubes and disengages them from the holders, the disengaged tubes being seated on the conical forms 82 of the seam setting mechanism by a rocker arm 84 fulcrumed on the bearing 85 and acting in the slot 55'. The plunger 81 is operated by a stem 86 which reciprocates in a cylinder 87. The plunger is moved toward the holder by a spring 88 engaging the rear end of the cylinder and a collar 89 on the stem, and is withdrawn by the engagement of its cam 90 with a cam 91 fixed on a revoluble shaft 92, the latter having a sprocket wheel 93 fixed thereon and driven by a chain 94 which passes over a sprocket wheel 95 fixed on the shaft 6. The arm 84 is oscillated by a link 96 and a lever 25 97 adapted to rock on the fulcrum 98 and having the roller 99. A cam 100 on the shaft 6 engages the roller and moves the lever in one direction and a lever 101, having a fulcrum 102 and provided with the 30 weight 103, is connected with the lever 97 to move it in the other direction. Auxiliary means for removing any tube that may stick in a holder are provided by a lever 129 rocked on its fulcrum 131 by a pin 130 on the slide 29; a link 132 connecting the lever 129 with a rod 133 movable longitudinally in the bearings 134; and a finger 135 on the rod 133 and movable thereby through the 35 slots 55' of the holders when the latter are 40 in a stationary position in the lower part of their course.

Conical seats or forms 82 are fixed to stems 104 by bearings 105, the stems are fixed to knuckles 106 adapted to rock in 45 bearings 107, sleeves 108 (provided with bearings 109 and 110) are movable longitudinally on the stems 104, springs 108' are disposed on the stems and sleeves between the bearings 105 and 109, crank levers 111 50 have the fulcrums 112 on the knuckles 106, pintles 113 connect the crank arms 111' having the cams 111^a with the bearings 110 and pintles 114 connect the crank arms 111'' with the shoes 115, the latter conforming to 55 and pressing the sections of the tubes containing the seams against the forms or rocking seats 82. The bearings 107 are fixed to cleats 116 which are secured to sprocket 60 chains 117 carried by sprocket wheels 118 and 119 fixed on the respective shafts 120 and 121 journaled in the frame; this mechanism being revolved by a sprocket wheel 122 fixed on the shaft 6, a sprocket wheel 123 fixed on the shaft 6 and a sprocket chain 65 124. As the link belt, formed by the cleats

116 and chains 117, moves the seam setting devices around the wheels 118 and 119, the wheel 56 moves in the opposite direction so that the respective holders 55 and forms 82 are brought into registration. A stationary cam 125 engages the cam 111^a of the registering form, rocks the crank lever 111 and draws back the corresponding shoe 115 against the action of the spring 108', while the parts 81 and 84 are operated to transfer the tube 54' from the holder to the form, whereupon the setting device which receives the tube is advanced so that the cam 111^a passes the cam 125 and the spring 108' rocks the crank lever 111 and presses the shoe 115 against the tube on the form, the pressure being maintained while the tubes are being carried in proximity to the heating coils 126 located beneath the belt. As the setting devices (which are turned by gravity in their bearings 107 to a position transverse to the belt in the lower part of their course) are carried around the wheels 119, a stationary cam 127 engages the cam 111^a, rocks the levers 111 and withdraws the shoes 115 from the tubes 54' which are thus permitted to fall from the forms 82. As the seam setting devices rise following the delivery of the tubes therefrom, they are brought to the horizontal position by the engagement of the knuckles 106 with a cam 128 fixed on the frame.

It will be understood that the several operations are timed so that the mandrel moves forward into a registering holder of 200 the stationary holder wheel, engages a blank which is passed thereto from the feeding table through the slot in the holder, and winds the blank within the holder while the pasting apparatus applies the adhesive 205 thereto. Then the mandrel is withdrawn from the tube and holder, the holder wheel is moved through a step, at the end of the step a tube is delivered from a holder to a setting device, and simultaneously the 210 mandrel is reinserted in a holder and a tube wound thereon, the finished tubes being discharged from the setting devices as they pass the cam 127.

Having described my invention, I claim: 215

1. In a tube making machine, the combination of revoluble winding means, setting means comprising seats for tubes and devices for pressing seams of tubes carried by said seats, means for carrying the tubes from the winding means to the setting means, and means for synchronizing the operations of said winding, setting and carrying means. 220

2. In a tube making machine, the combination of a tube winding device, means for revolving said device, means for moving said device longitudinally, a holding device in which tubes are wound by said first device, means for moving said holding device intermittently, a setting device, means for mov- 225 230 235 240 245 250 255 260 265 270 275 280 285 290 295 300 305 310 315 320 325 330 335 340 345 ing said setting device, and means for transferring tubes from said holding device to said setting device.

3. In a tube making machine, the combination of a plurality of movable tube holders, means for moving said holders intermittently, a tube winding mandrel, means for revolving said mandrel, means for moving said mandrel into and out of said holders, means for applying an adhesive to blanks wound upon said mandrel in said holders, setting means for pressing together the laminations of tubes, means for transferring tubes from said holders to said setting means, and means for synchronizing the operations of the several means aforesaid.
4. In a tube making machine, the combination of a revoluble mechanism provided with a plurality of holders, a reciprocating mechanism comprising a mandrel movable into and out of said holders, a revoluble mechanism provided with devices for pressing tubes, mechanism for transferring tubes from said holders to said devices, and means for synchronizing the operations of said mechanisms.

5. In a tube making machine, the combination of a revoluble wheel provided with a plurality of holders, means for revolving said wheel intermittently, a mandrel, means for revolving said mandrel and moving it into and out of said holders, a link belt, means for moving said link belt, seam setting devices carried by said link belt into registration with said holders, means for transferring tubes from said holders to said seam setting devices, and means for synchronizing the longitudinal movement of said mandrel, the revolution of said wheel, the movement of said link belt and the action of said tube transferring means.

6. In a tube making machine, a revoluble and longitudinally movable shaft, a mandrel carried by said shaft, mechanism for revolving said shaft, mechanism comprising a cam for moving said shaft longitudinally, a revoluble wheel provided with a plurality of holders movable into alinement with said mandrel, said mandrel being movable into and out of the respective holders aforesaid, mechanism for turning said wheel intermittently when said mandrel is withdrawn therefrom, a plurality of setting devices comprising forms movable into registration with said holders and shoes adapted for pressing tubes on said form, means for moving said setting devices synchronously with the movements of said wheel whereby said forms and holders are brought into registration, means for withdrawing said shoes from said forms to permit the transfer thereto of tubes from said holders, and means for transferring tubes from said holders to said forms.

7. In a tube making machine, the combination of a revoluble driving shaft, a revolu-

ble driven shaft, a cam on said driven shaft, a revoluble mandrel shaft, means whereby said driving shaft revolves said mandrel shaft, means whereby said cam moves said mandrel shaft longitudinally, a mandrel comprising a body and a sleeve having means for engaging a blank, means whereby said mandrel shaft operates said body and sleeve to engage in the forward longitudinal movement thereof and to disengage in the rearward movement thereof, a revoluble wheel having holders in which said mandrel is inserted in its forward movement and from which it is withdrawn in its rearward movement, means for revolving said wheel when said mandrel is withdrawn from said holders, a revoluble segment for applying an adhesive to blanks in process of winding on said mandrel, means for revolving said segment in synchronism with said mandrel, tube pressing devices, means for revolving said wheel, and means for transferring tubes from said holders to said pressing devices.

8. In a tube making machine, carrier mechanism provided with a plurality of holders, a reciprocating shaft, a sleeve on said shaft and having a limited longitudinal movement relative thereto, means for limiting the movement of said sleeve, a second sleeve relative thereto said first sleeve has a limited longitudinal and rotary movement, a spring disposed between said sleeves, a second shaft longitudinally fixed and revolubly movable relative to said first shaft, a mandrel body connected to said second named shaft and adapted to turn relative to said second sleeve, a mandrel sleeve fixed to said second sleeve, means connecting said first named sleeve and second named shaft whereby the longitudinal movement of one relative to the other effects their relative rotary movement, and means for reciprocating said mandrel body and sleeve into and out of said holders.

9. In a tube making machine, carrier mechanism provided with holders, a reciprocating slide, a shaft journaled in said slide, a sleeve on said shaft and having a limited longitudinal movement relative thereto, a spring on said shaft between said slide and sleeve, means for limiting the movement of said sleeve, a second sleeve, a mandrel comprising a body connected with said shaft and a sleeve connected with said second sleeve, means connecting said shaft and said first sleeve and comprising a cam slot in one and a pin connected with the other, and means for reciprocating said slide, whereby said mandrel is moved into and out of said holders and the parts of said mandrel are moved relatively.

10. In a tube making machine, a shaft having a cam thereon, mechanism comprising a shaft having a mandrel thereon reciprocated by said cam, mechanism whereby

5 said first shaft revolves said second shaft intermittently, carrier mechanism having holders revoluble on said first shaft, said holders having apertures through which blanks are fed to said mandrel, mechanism adapted for receiving tubes from said carrier mechanism and for pressing seams of said tubes, and means whereby said first shaft revolves said carrier mechanism intermittently and moves said holders into registration with said mandrel.

10 11. In a tube making machine, a shaft having journaled thereon a wheel provided with holders, a gear fixed to said wheel, a 15 revoluble gear engaging said gear first named, mechanism whereby said shaft revolves said second gear intermittently, a reciprocating mandrel movable into and out of said holders, means for reciprocating said mandrel intermittently into and out of the respective holders, and means for revolving said mandrel within the respective holders.

12. In a tube making machine, a shaft having thereon cam mechanism and carrier mechanism provided with holders extending 25 in the direction of said shaft, intermittently acting driving mechanism operated by said shaft, mechanism comprising a shaft substantially parallel with said first shaft and 30 having a mandrel thereon reciprocated by said cam mechanism intermittently and revolved by said driving mechanism intermittently in synchronism with the revolution of said carrier mechanism, said mandrel being reciprocated by its shaft substantially parallel to the axis of said carrier mechanism into and out of said holders, mechanism comprising a revoluble shaft and a device for applying an adhesive 35 40 revoluble by said driving mechanism intermittently in synchronism with the revolution of said mandrel shaft, mechanism for ejecting tubes from said holders, and mechanism which receives and presses tubes ejected 45 from said holders, said last named mechanism being movable about an axis parallel with the axis of said carrier mechanism.

13. In a tube making machine, a wheel having thereon holders containing slots, a 50 revoluble mandrel, means for intermittently revolving said wheel and reciprocating said mandrel into and out of said holders, said mandrel having automatic means for engaging a blank fed through said slot, intermittently acting means for applying an adhesive to blanks fed to said mandrel, a bridge adjacent to said wheel for guiding blanks to said holders, and means for moving said bridge out of the path of said blanks.

55 60 65 14. In a tube making machine, a revoluble wheel having holders fixed thereto, means for revolving said wheel intermittently, a mandrel having means for engaging a blank, means for reciprocating said mandrel

into and out of said holders, means for revolving said mandrel and rolling blanks into tubes within said holders, means for ejecting said tubes from said holders, forms for receiving tubes ejected from said holders, shoes for pressing tubes carried by said forms, and means for operating said shoes.

15. In a tube making machine, a wheel having holders thereon, a mandrel revoluble in said holders and adapted to form tubes 75 therein, means for ejecting tubes from said holders, and means for receiving and pressing tubes ejected from said holders.

16. In a tube making machine, a carrier having holders thereon, a mandrel revoluble 80 within said holders for forming tubes therein, means for ejecting tubes from said holders, rocking seats for receiving said tubes, shoes for pressing tubes on said seats, levers connected with said shoes, and cams for 85 rocking said levers to operate said shoes.

17. In a tube making machine, a revoluble wheel having holders for carrying tubes, in combination with a link belt having tube pressing devices thereon, means for moving 90 said wheel and belt so as to bring said holders and devices into registration, and means for transferring tubes from said holders to said devices.

18. In a tube making machine, a revoluble drum having a cam-way, means comprising a slide reciprocated by said drum through said cam-way, means comprising a shaft revoluble in said slide and a mandrel connected with said shaft, means comprising a revoluble shaft and a segmental roller for applying paste to a blank, a roller for pressing said blank against said segmental roller, means whereby said slide moves said first named shaft longitudinally, and means 95 whereby said shafts are revolved intermittently in synchronous relation to each other and to the longitudinal movement of said shaft.

19. In a machine for making tubes, a 110 link belt, means for moving said belt, a bearing carried by said belt, a form journaled on said bearing, a shoe, means whereby said shoe is connected in movable relation to said form, means for automatically 115 drawing said shoe toward said form, and means in the path of movement of said means first named for withdrawing said shoe from said form.

20. In a tube making machine, a link 120 belt, wheels for carrying said belt, means for revolving said wheels and moving said belt intermittently, bearings carried by said belt, forms fulcrumed on said bearings, shoes for pressing tubes against said forms, 125 levers fulcrumed relatively to said forms for carrying said shoes, springs whereby said levers press said shoes toward said forms, and means in the path of said levers for rocking them against the action 130

- of said springs and withdrawing them from said forms.
21. In a tube making machine, a revolute wheel having tube holders, in combination 5 with means comprising a traveling link belt, bearings fixed on said belt, forms fulcrumed on said bearings, crank levers fulcrumed relatively to said forms, shoes carried by said crank levers, means comprising 10 springs whereby said crank levers press said shoes toward said forms, means for engaging said levers and withdrawing said shoes from said forms, means for moving said wheel and belt so as to bring the respective forms and holders into registration 15 successively, and means for transferring tubes from said holders to said forms registering therewith.
22. In a tube making machine, a link belt, 20 means for moving said belt, bearings carried by said belt, forms fulcrumed on said bearings so as to rock transversely to said belt, levers fulcrumed relatively to said forms, shoes carried by said levers, means comprising 25 springs for operating said levers to move said shoes toward said forms, tube holders, means for moving said tube holders intermittently in synchronous relation to the movement of said belt whereby said 30 holders and forms are brought into registration, a device whereby said levers are rocked to withdraw said shoes from said forms when said holders are in registration therewith, means operating intermittently 35 in synchronous relation to the movements of said forms and holders for transferring tubes from said holders to said forms, and means for withdrawing said shoes from said forms to release tubes thereon.
- 40 23. In a tube making machine, a revolute wheel provided with tube holders, a revolute belt provided with devices for pressing tubes, means for moving said wheel and belt whereby said holders and devices are 45 brought into registration, and reciprocating
- mechanism for pushing tubes in said holders toward said devices, said mechanism comprising a stem having means for engaging a cam, and a revolute cam engaging said stem for moving it longitudinally. 50
24. In a tube making machine, a revolute shaft, a revolute wheel provided with tube holders, a revolute mechanism provided with tube pressing devices, means whereby said shaft revolves said wheel and mechanism, reciprocating plunger mechanism for moving tubes in said holders toward said devices, a revolute cam for operating said plunger mechanism in one direction, a spring for operating said plunger mechanism in the opposite direction, and means whereby said shaft revolves said cam. 55
25. In a tube making machine, tube winding mechanism; a revolute shaft, revolute mechanism for holding tubes wound by said winding mechanism, revolute pressing mechanism, mechanism whereby said shaft revolves said holding and pressing mechanisms, a fulcrumed arm for transferring tubes from said holding to said pressing mechanism, and mechanism comprising a cam on said shaft whereby said arm is oscillated. 60
26. In a tube making machine, a revolute shaft, a revolute wheel provided with tube 75 holders, a link belt provided with seam setters, revolute wheels for carrying said link belt, mechanisms whereby said shaft revolves said wheels, mechanism for discharging tubes from said holders, and means comprising a cam revolved by said shaft for operating said mechanism last named. 80
- In testimony whereof I have hereunto set my hand this 25th day of June, 1813, in the presence of the subscribing witnesses. 85
- MAX QUAAS.
